UNITED STATES PATENT OFFICE.

WILLIAM H. WINSLOW AND FRANCIS A. WINSLOW, OF CHICAGO, ILLINOIS.

BUILDING CONSTRUCTION.

SPECIFICATION forming part of Letters Patent No. 609,487, dated August 23, 1898.

Application filed November 26, 1897. Serial No. 659,764. (No model.)

To all whom it may concern:

Be it known that we, WILLIAM H. WINSLOW and FRANCIS A. WINSLOW, citizens of the United States of America, residing at 5 Chicago, in the county of Cook and State of Illinois, have invented new and useful Improvements in Building Constructions, of which the following is a specification.

Our invention relates to certain new and 10 useful improvements in building constructions, and more especially to that class of building construction adapted for use in libraries and the like, where neatness, strength, and durability are required. 15 To such end it consists in a light, simple, and substantial framework containing certain novel features of construction, a description of which will be found in the following specification, and the essential features thereof 20 definitely pointed out in the claims appended hereto.

The invention is clearly illustrated in the drawings furnished herewith by means of five figures, of which—

25 Figure 1 is a side elevation of my construction. Fig. 2 is an end elevation, partly broken away. Fig. 3 is a vertical cross-section in line 3 3 of Fig. 1. Fig. 4 is a central vertical longitudinal section through the device, certain portions being broken away to enable the view to be made as large as possible upon the sheet; and Fig. 5 is a horizontal section in line 5 5 of Fig. 4. Figs. 2 to 5, inclusive, are upon a larger scale than Fig. 1 in order to 35 more clearly illustrate the invention.

In the views, A A' A² A' A represent uprights or supporting members resting upon a suitable foundation and preferably bolted thereto.

40 B B' B² are horizontal members adapted to hold the uprights together and at proper distances from each other. The frame thus formed is braced by a truss C, extending diagonally from the middle of the frame to the angles made by the uprights A' A' and horizontal members B B². This truss is adjustable for the purpose of truing up the frame and bracing it against longitudinal strain.

45 The different members of the frame are shown as of peculiar construction, and I will now proceed to describe each separately. The uprights are each composed of a bar or

supporting-web a, (see Figs. 4 and 5,) slit at the bottom and the two ends bent at right angles to the main portions in opposite directions to form feet a', adapted to be screwed or bolted to the floor. Upon both faces of the uprights A' A² and upon the inner faces of the uprights A are provided clamp-bars a², preferably narrower than the web a, spaced 55 apart therefrom slightly and secured thereto in any suitable manner. These bars are adapted to support shelf-brackets (seen in Fig. 3) provided with suitable clamping means for adjustably securing them to the 60 clamp-bars. The clamp-bars not only form a supporting means for the brackets, but also stiffen the uprights, thereby increasing the 65 rigidity of structure.

The horizontal members consist of tubes b, 70 extending between the webs a, tie-rods b', passing through the tubes and webs, and nuts b² upon the ends of the tie-rods. By tightening up these nuts a rigid frame is formed; but in order to give it still greater 75 rigidity I provide the frame with a truss C, which consists of four diagonally-extending tubes or rods. Upon the ends of these tubes are secured crotches c c', adapted to engage the framework at the intersections 80 made by the members A' A', B' B², and A² A'. The crotches c are, however, provided with screws c², the ends of which rest against the web of the upright A², and by adjusting these screws the various parts of the truss may be 85 moved longitudinally along the horizontal member B until the frame is adjusted in perfect alignment and rigidly braced.

It should be noticed that the different parts of this construction are simple and cheap, thus 90 lessening the cost and at the same time simplifying the structure.

We claim as new and desire to secure by Letters Patent—

1. In a building construction for library-shelving or the like, the combination with uprights each comprising a main supporting-web and clamp-bars secured thereto, of horizontal connecting members comprising tubes extending from upright to upright, tie-rods 95 passing through the same and connecting them together and braces extending between diagonally-opposite angles of the structure and provided with adjusting-screws adapted 100

to vary the length of the diagonals and thereby true up and brace the structure; substantially as described.

2. A building construction for library-shelving or the like comprising webs, a , clamp-bars, a^2 , secured thereto, tubes extending between the webs, tie-rods passing through the tubes and webs and connecting the parts together, diagonal braces extending diagonally from approximately the middle of the center web, crotches in the ends of said diagonal braces engaging the tubes and webs and set-screws in the inner crotches bearing against the central web; substantially as described.
3. A building construction comprising uprights, A , A' , A^2 , horizontal connecting-bars,

B , B' , B^2 , a truss extending from approximately the center of the frame and to the upper and lower horizontal member thereof and set-screws threaded in said truss and engaging the upright, A^2 , substantially as and for the purpose set forth.

In witness whereof we have hereunto set our hands, at Chicago, in the county of Cook and State of Illinois, this 18th day of November, A. D. 1897.

WILLIAM H. WINSLOW.
FRANCIS A. WINSLOW.
